UNITED STATES PATENT OFFICE.

HERMAN F. BALL, OF NEW YORK, N. Y.

OPERATING MECHANISM FOR DUMPING-CARS.

No. 845,920.

Specification of Letters Patent. Patented March 5, 1907.

Application filed October 8, 1906. Serial No. 338,071.

To all whom it may concern:

Be it known that I, HERMAN F. BALL, a citizen of the United States, residing at New York, in the county of New York and State of New York, have invented certain new and useful Improvements in Operating Mechanism for Dumping-Cars, of which the following is a specification.

My invention relates to operating mech-

anism for downwardly swinging doors or bottom members and particularly to the operating mechanism for the drop bottom Gondola type of cars having inclined floors leading to the doors, and the invention has for its objects; to provide an operating mechanism so arranged as to provide for a minimum effort of the operator when closing the doors; to provide a mechanism wherein the operating handle may be manipulated and the doors allowed to open without danger to the operator; to provide an improved door operating mechanism adapted to hold the door more securely closed than has heretofore been done; and finally to provide an operating mechanism having a holding or locking means supplementary of the flexible closing means and adapted to be thrown into position and out of position by the operation of the handle in closing and opening the doors.

These and other objects are accomplished by my invention, one form of which is illustrated in the accompanying drawings, in which, Figure 1 is a side elevation of the mechanism, the framework of the car inclosing such mechanism being broken away to more clearly disclose the parts, and the doors being in closed position.

Figure 2 is a view similar to that of Figure 1 with the doors in open position.

Figure 3 is an end elevation of the construction as shown in Figure 1.

Figure 4 is a plan view of the parts in the position shown in Figure 1, the framework of the car above being broken away to more clearly disclose the parts.

Figure 5 is a detailed view of the drum and the slip connection between the drum and locking means.

Figures 6, 7, and 8, are details showing the various parts of the mechanism as illustrated in Figure 5; and

Figure 9 is a detail side view of the holding bracket.

The construction set forth is particularly applicable to cars although it may be applied

to gravity opening doors of any kind, and the type of cars for which the construction is especially designed is the well known Gondola cars with drop doors. The construction of the car proper constitutes no part of this invention and for this reason only so much of the car is illustrated as is necessary to indicate the location of the operating mechanism and the manner of supporting it. It has been common heretofore to operate swinging doors of the type shown by means of a handle connected to a drum having a flexible connection with the doors. The doors are ordinarily held in closed position by means of a pawl coacting with a ratchet upon the drum and in order to release the doors and dump the car, it is necessary to throw the pawl, which operation has heretofore been very dangerous because of the great force and speed with which the handle under the influence of the weight upon the doors revolves and many serious accidents have resulted from this manner of operation. My invention is designed to do away with this danger and with this end in view, means are provided whereby the handle may be revolved and the flexible means unwound before the weight of the door is thrown thereon together with means for automatically releasing the door at the end of this reverse movement of the handle. The construction is also designed, as before indicated, to take the strain of supporting the door off the flexible raising means after such door is raised, and by virtue of the toggle action of the links to provide a mechanism which can be operated with minimum effort.

The operating mechanism is preferably located at the center of the car between the sills 1-1 as indicated in Figures 3 and 4, and is protected from injury and dirt from above by means of the member 2 passing across the top of the sills. As shown in the main assembled views 1, 2, 3, and 4, the principal parts of the device are the doors 3, 3 which may be of any improved type and are hinged to the hopper like bottom of the car 4 in the usual way, 5 is a rotary lifting member secured to the beams 1, 1 at the axis 6 and by means of the brackets 7 (Figure 3), 8, 8 are the links pivoted at one end to the doors and at the other end to the member 5 at the common axis 9, 10 is the operating shaft carrying the drum 11, upon which drum the chain 12 is wound at one end while the other end passes around the sheave like portion of the

member 5 and is secured to such member 5 by means of the staple 13, 14 is the ratchet on the end of the shaft 10 which ratchet is held by the pawl 15, 17 is a lever and collar member having a slip connection to the drum 11, the purpose of which will be set forth more fully hereinafter, and 18 is the connecting rod between the operating member 5 and the lever 17.

Referring now more particularly to the details of construction it will be noted that the rotary member 5 which operates the links 8 is provided at one side as heretofore referred to, with a sheave 19 over which the chain 12 is designed to pass, and the central portion of such member is recessed so that when the members are in position shown in Figure 1, the links 8, 8 are received in such recess thereby allowing the links to move as far to the right as is desirable and also supporting them laterally to prevent a turning movement on the pivots. As indicated in Figure 3, the lower ends of the links 8 are forked to receive the ends of the members 20, which members 20 extend through the doors and are provided with bolts 21 on their outside ends. It will be noted from Figure 1 in which the doors are shown in closed position, that the pivotal point 9 from which the links 8 depend, is slightly to the right of the pivot 6 so that the weight of the doors and the material thereon tends to move such pivot point 9 to the right instead of to the left and therefore when the parts are in this position there is no tendency of the doors to open, and in fact they are held securely shut. The member 5 is prevented from moving farther to the right under the weight of the doors and the material by the connecting rod 18 heretofore referred to, which rod is pivoted at one end to the member 5 and at the other end to the member 17 operated from the drum 11.

The locking attachment just referred to also constitutes a means whereby the danger of operating the crank when the doors are to be opened is avoided which means will now be described in detail, reference being had particularly to the detailed showings in Figures 5 to 8. The member 17 consists of a collar provided with a lever arm 18', the collar being loosely mounted upon the shaft 10 and being recessed upon the side toward the drum 11 which recess is, as shown, in Figure 8, provided with an inwardly projecting lug 23. A second collar 24 is loosely mounted upon the shaft 10 intermediate the member 17 and the drum 11 which member 24 has a lug 25 projecting from the side and adapted to engage the lug 23. A third collar 26 is mounted upon the shaft 10 intermediate the collar 26 and drum 11, which member has on opposite sides thereof, lugs 27 and 28 respectively, as indicated in Figure 7, the lug 27 being adapted to engage a lug 29 projecting

from the end of the drum 11, and the lug 28 being adapted to engage the lug 25 on the collar 24, or additional collars with lugs if more slip is desired and such collars are added. This arrangement constitutes a slip connection which is designed to cause only a slight movement of the member 17 and the connecting rod 18 while the drum 11 is being rotated a sufficient distance to raise the doors to closed position. The drum 11 will rotate nearly a full revolution before its lug 29 will engage the lug 27 on the collar 26, and the collar 26 will rotate nearly a full revolution before its lug 28 will engage the lug 25 on the collar 24 and the collar 24 will rotate nearly a full revolution before its lug 25 will engage the projection 23 of the member 17, or in other words the drum 11 will rotate over two revolutions before the arm 18 will be positively operated, but after such engagement the parts will all rotate together. The arrangement whereby a plurality of turns of the operating lever are secured reduces the power necessary to operate the lever and such feature is necessitated by the great weight of the doors. It will also be apparent that on the reverse movement the drum will have to be rotated over two revolutions before the member 18 will be started in its return movement. When the doors are in open position it will be seen from Figure 2 that the connecting rod 18 will occupy the position as indicated, the arm 18' being in substantially a vertical position. When the shaft 10 is revolved a trifle over two revolutions the member 5 will be rotated raising the links 8, 8 and bringing the parts into the position shown in Figure 1 and the rod 18 will be moved to the right by virtue of its engagement with the member 5 during which time the slip connection including the collars 24 and 26 coating with the drum and the member 17 will allow the shaft to rotate freely. Just before the arm 18 reaches the position shown in Figure 2, however, the lugs of the slip connection will come into engagement and the arm 18 moved positively to the right. As the radius upon which the arm 18' swings is greater than the radius of the winding drum and the pivot point 30 of the member 18 is nearer to the axis of the member 5 than is the sheave 19, the positive actuation of the member 18 at the end of the stroke produces the slack in the chain 12 as indicated in Figure 1. The connecting rod 18 will, when in the position shown in Figure 1, constitute a locking device for the member 5 and consequently the doors, for the reason that the pivotal points 30 and 31 of the rod will be on a line with the axis of the drum 11. The member 18 is permitted to move to this position by virtue of the bend 32, which bend 32, fits over the drum. It will be apparent from the foregoing that the member 18' in the position shown constitutes a supple-

mental locking means and that even in case of a tendency to jar the pivot 9 to the left no strain would be thrown upon the flexible member 12. The drum is, as heretofore indicated, held positively in position by means of the pawl 15 secured to the side of the car, which pawl 15 is held in position by means of the cam member 33.

The operation in opening the doors is as follows: The pawl 15 having been released, the handle upon the shaft 10 is revolved a sufficient number of turns to unwind the chain 12. During this time the doors cannot open because, as before stated, the pivot point 9 is to the right of the supporting pivot 6 of the member 5 and furthermore the member 18' remains in the position indicated in Figure 2 until the shaft 10 has revolved a sufficient number of times in a reverse direction to cause the lugs of the slip connection to form a rigid connection and rotate the arm, 18' to the left. This, of course, brings the pivot 9 to such a position that the doors open by virtue of the weight of the material upon them and the slack of the chain is taken up. There is, however, no jerk upon the handle as it will be apparent that the slip connection provides for the revolutions of the drum incident to the opening of the doors before the lug on the collar positively engages the member 17. There will therefore be no danger to the operator in releasing the pawl and in maintaining his hold upon the handle.

Having thus described my invention and illustrated its use, what I claim as new, and desire to secure by Letters Patent, is the following:

1. In combination, a gravity opening door, an operating shaft, an operative connection between the shaft and door, means independent of the operative connection for holding the door closed, and means operable by the shaft to release such holding means after the operative connection has been moved to a position to allow the door to open.

2. In combination, a gravity opening door, an operating shaft, a flexible operative connection between the shaft and door, means independent of the flexible connection for holding the door closed, and means operable by the shaft to release the holding means when the flexible connection has been unwound from the shaft sufficiently to allow the door to open.

3. In combination, a gravity opening door, an operating shaft, an operative connection between the shaft and door, means independent of the operative connection for holding the door closed, and means operable by the shaft to move such holding means to securing position after the door is closed.

4. In combination, a gravity opening door, an operating shaft, an operative connection between the shaft and door, means independent of the operative connection for holding

the door closed, and means operable by the shaft to move such holding means to securing position when the shaft is rotated in one direction and to release such holding means when the shaft is reversely rotated.

5. In combination, a pair of swinging gravity opening doors, links and a rotatable member secured thereto for closing the doors, a rotatable operating shaft, a flexible connection between the member and the shaft, an independent connection extending from the member to a position adjacent the shaft for holding the door closed, and means connected to the shaft whereby such independent connection is released on the rotation of the shaft after such reverse movement has unwound the flexible connection.

6. In combination, a pair of swinging gravity opening doors, links and a rotatable member secured thereto for closing the doors, a rotatable operating shaft, a flexible connection between the member and the shaft, an independent connection extending from the member to a position adjacent the shaft for holding the door closed, and means connected to the shaft whereby such independent connection is brought into operation when the doors are closed and whereby such independent connection is released on the reverse rotation of the shaft after such reverse movement has unwound the flexible connection.

7. In combination, a swinging gravity opening door, a rotatable member secured thereto for closing the door, a rotatable operating shaft, a flexible connection between the member and shaft, a link connected to the member and extending to a position adjacent the shaft, and a slip connection between the link and shaft whereby the link is moved to a locking position during the latter part of the rotation of the shaft.

8. In combination, a swinging gravity opening door, a rotatable member secured thereto for closing the door, a rotatable operating shaft, a flexible connection between the member and the shaft, a link connected to the member and extending to a position adjacent the shaft and a collar connected to the link and having a slip connection on the shaft whereby the link is moved to a locking position during the latter part of the forward rotation of the shaft and whereby the flexible connection is unwound from the shaft during its reverse rotation before the link is moved from its locking position.

9. The combination with a gravity opening door, drum and flexible operating means, of a locking means and a slip connection between the drum and locking means, whereby the locking means is moved to holding position during the latter part of the forward movement of the drum and is moved to unlocked position during the latter part of the reverse movement of the drum.

10. The combination with a gravity opening door, drum and flexible operating means, of a locking means and a slip connection between the drum and locking means comprising a locking member and a collar having a lug, together with a co-operating lug operable by the drum whereby the locking means is moved to holding position during the latter part of the forward movement of the drum and is moved to unlocked position during the latter part of the reverse movement of the drum.

11. The combination with a gravity opening door, drum and flexible operating means, of a locking means and slip connection between the drum and locking means comprising a lug on the drum, a locking member, a collar connected thereto and provided with a lug, and an interposed loose second collar provided with lugs on opposite sides for co-operating with the other lugs whereby the locking means is moved to holding position during the latter part of the forward movement of the drum and is moved to unlocked

position during the latter part of the reverse movement of the drum.

12. The combination with a gravity opening door, drum and flexible operating means, of a locking means and slip connection between the drum and locking means comprising a lug on the drum, a rigid locking member, a collar secured to the locking member and provided with a lug, and a plurality of loose collars having lugs interposed between the drum and the first collar whereby a slip connection is secured and the rigid locking member is moved to holding position during the latter part of the forward rotation of the drum and is moved to unlocked position during the latter part of the reverse rotation of the drum.

In testimony whereof I have hereunto signed my name in the presence of the two subscribed witnesses.
